UNITED STATES PATENT OFFICE

NORTON A. MEARS AND DIBRELL P. HYNES, OF CHICAGO, ILLINOIS, ASSIGNEES TO
CHICAGO FORGING & MANUFACTURING CO., OF CHICAGO, ILLINOIS, A CORPORATION
OF ILLINOIS

HOOD LATCH

Application filed September 19, 1931. Serial No. 563,710.

Our invention relates to an improvement in supporting abutments for hood latches of the type shown for example in Patent No. 1,809,720, issued June 9, 1931. One object of our invention is the provision of improved abutment means for supporting a flexible locking rock shaft. Another object is the provision of an improved form of locking rock shaft lever. Another object is the provision of supporting means for the locking rock shaft of such a hood latch which shall be invisible from the exterior of the hood. Other objects will appear from time to time in the course of the specification and claims.

We illustrate our invention more or less diagrammatically in the accompanying drawings, wherein

Figure 1 is an elevation;

Figure 2 is a partial side elevation on a larger scale;

Figure 3 is a section on the line 3—3 of Figure 2;

Figure 4 is an inside elevation of the latch proper;

Figure 5 is a section on the line 5—5 of Figure 4;

Figure 6 is a plan view of the structure shown in Figure 4;

Figures 7, 8 and 9 are details;

Figure 10 is an inside elevation of a variant form;

Figure 11 is a section on the line 11—11 of Figure 10; and

Figure 12 is a section on the line 12—12 of Figure 10.

Like parts are indicated by like symbols throughout the specification and drawings.

Referring to the drawings, A generally indicates an automobile hood closure, A¹ indicates any suitable portion of the automobile structure or frame to which is secured a locking abutment generally indicated as B.

The member B includes a base plate B¹ which may be bolted or otherwise secured to the frame portion A¹ as by the screws B², the nuts B³ and the washers B⁴. B⁵ indicates the locking abutment stem or member proper, outwardly extending from the base plate B¹.

C indicates a rock shaft rotatably mounted within the hood A. The rock shaft may in-

clude a central offset or crank portion C¹ and terminal cranks C², indicated, as in Figure 5, as being in part arcuate as at C³, preferably in the normal locking position, the point of engagement between the curved portion C³ and the locking abutment B⁵ is somewhat above the axis of rotation of the rock shaft C. This disposition of parts will be clear from Figures 4 and 5.

In order to support the rock shaft we may employ bearing stirrups generally indicated as D as shown for example in detail in Figures 4 and 5. The member D includes pads or flanges D¹ which may be welded or otherwise secured to the interior of the hood A, in such fashion that no exterior mark is shown and no exterior perforation is made in the hood. D² indicate offset intermediate portions connected by a stirrup or seat D³ in which the rock shaft seats, as shown for example in Figure 5. D⁴ is a closure plate which may be bolted or otherwise secured to the faces of the members D², as shown in Figure 5, to complete the bearing for the rock shaft C and to hold the rock shaft seated in the bearing. We illustrate for example the bolts D⁵ which are shown as having square heads D⁶. The bolt shanks penetrate apertures D⁷ and the heads are admitted through the enlarged apertures D⁸ shown in dotted line in Figures 4 and 8 and in full line in Figures 5 and 6. D⁹ indicate any suitable nuts. It will be seen that the bolts D⁵ may readily be removed but that when the nuts are employed to lock them in the position in which the parts are shown in Figures 2 and 3 a closed bearing is provided for the rock shaft C.

The intermediate portion of the rock shaft may be mounted upon a base plate generally indicated as C⁴, which plate may have at a lower edge the bearing sleeves C⁸ offset or curled up from the stock of the plate C⁴. The plate C⁴ may penetrate at its upper edge, within the bracket generally indicated as C⁵, the ends of which may be spot welded as at C⁶. This bracket may be so formed that the plate is slidably insertable into it. It may be held in position by bearing sleeves or brackets positioned at each side of the

plate, which serve to hold the rock shaft C against that lateral movement, thereby preventing movement of the plate C⁴. We may employ for example brackets identical with 5 those shown in Figures 4 and 5, as indicated for example in Figure 2. By pushing one bracket adjacent each edge of C⁴ lateral movement of the plate is prevented, the brackets also preventing movement of the plate toward 10 or away from the inner face of the hood.

Any suitable means may be employed for rotating the rock shaft.

We illustrate the exteriorly operable 15 handle G, the interior crank arm G¹ rotated thereby and the link G², one end of which is pivoted to the crank G¹, the other being looped about the crank offset C¹ as at G³. G⁴ are any suitable stops upset in the plate C⁴ 20 and serving to limit the crank G¹ to a predetermined arc of rotation. The crank is provided with an extension G⁵ closely approaching the inner face of the plate C⁴ and adapted to engage the stops G⁴.

25 Referring to the form of Figures 10, 11 and 12, we provide a slight variation of our device wherein the rock shaft C is somewhat inwardly spaced from the inner face of the closure A. We illustrate for example brackets H including end portions H¹ which may be spot welded or otherwise secured to the inner face of the closure A. The inwardly spaced portion H² is connected thereto as by the side members H³. A bearing loop H⁴ 30 is applied to the face of the member H² and end portions H⁵ thereof are bolted to the member H² as by the square headed bolts H⁶. The side portions H⁸ are apertured as at H⁷ to permit the passages of the heads 35 of these bolts and the member H² is slotted as at H⁸ to permit the lateral movement of the shank of the bolt. H⁹ H¹⁰ indicate any 40 suitable nuts adapted to lock assembly together. The plate C⁴ is correspondingly inwardly spaced from the inner face of the closure A and we illustrate it in Figures 10 and 11 as mounted on brackets H¹⁰, which 45 correspond to the brackets H, but are provided with a plurality of members or portions H² as shown in detail in Figure 11.

50 It will be realized that whereas we have described and shown a practical and operative device, nevertheless many changes might be made in size, shape, number and 55 disposition of parts without departing from the spirit of our invention. We wish, therefore, that our drawings might be taken as in a broad sense illustrative and diagrammatic rather than as limiting us to our specific showing.

59 The use and operation of our invention are as follows:

In applying the hood latch to the closure it is advantageous to be able to apply the 65 hood latch assembly practically as a unit.

For example the stirrups or brackets H and H¹⁰ or D are already spot welded or otherwise secured to the closure when the closure is applied to the car. This is also true of the bracket C⁵, as shown in Figures 1 and 2. 70 The base plate C⁴ may be delivered to the assembly line with the rock shaft already penetrating the sleeve C⁸ of the plate C⁴. Axial movement of the rock shaft is prevented by the crank offset at the center of the rock shaft. The operator then inserts and assembles the handle assembly. The link G² is supplied with the rock shaft and the operator may connect the link with the crank G¹ and place the handle assembly in the condition in which it is shown in Figures 2 and 80 3. He also applies the holding plates or stirrups or loops H⁴ or D⁴, inserting the necessary bolts and tightening the nuts.

85 For example, when the auto goes down the assembly line in the course of manufacture, the stirrup member D is preferably already welded or otherwise secured to the interior of the hood A. The workman in the assembly line merely has to slip in the bolts D⁵, and thread the securing plate D⁴ upon them. The apertures of the securing plate D⁴ hold the bolts against any outward movement along the slots D⁶. The nuts D⁹ lock the 90 plate D⁴ firmly in position. The result is an easily assembled bearing for the rock shaft which renders application of the rock shaft to the hood quick and easy and prevents any exterior deformation or disfigurement of the hood. While we do not wish to be limited to any specific means for securing the stirrup or brackets to the hood we 95 illustrate them as spot welded.

100 It will be clear that we have illustrated an automobile hood latch assembly which is in large part preassembled and which can be readily applied, in the assembly line, with a minimum of time and trouble.

We claim:

110 1. In a support for shafts, a relatively extended supporting member, a base plate associated therewith, said base plate including integrally formed bearing sleeves for said shaft, and additional bearing and securing means for said shaft including brackets secured to the extended member and adapted to receive the shaft, and closure members for said brackets adapted to hold the shaft in operative relation with said brackets, said closure members being removably secured to said brackets.

115 2. In a support for shafts, a relatively extended supporting member, a base plate associated therewith, said base plate including integrally formed bearing sleeves for said shaft, and additional bearing and securing means for said shaft including brackets secured to the extended member and adapted to receive the shaft, and closure members for 120 said brackets adapted to hold the shaft in 125 said brackets.

130

operative relation with said brackets, said closure members being removably secured to said brackets, a pair of said brackets being positioned, one on each side of said base plate and being adapted to prevent endwise movement of the base plate along the axis of the shaft.

3. In a support for shafts, a relatively extended supporting member, a base plate, said base plate including integrally formed bearing sleeves for said shaft and additional bearing and securing means for said shaft including brackets secured to said relatively extended member and adapted to receive the shaft and closure means for said brackets, removably secured thereto.

4. In a support for shafts, a relatively extended supporting member, a base plate for said rock shaft, said base plate including integrally formed bearing sleeves for said shaft and additional bearing and securing means for said shaft including brackets secured to said relatively extended member and adapted to receive the shaft and closure means for said brackets, removably secured thereto, and a retaining member for an edge of the base plate remote from the shaft, said member including a socket upon the relatively extended member into which the edge of the base plate may slidingly penetrate.

5. In a shaft bearing, a relatively extended supporting member, bearings for the shaft including brackets secured to the extended member and adapted to receive the shaft, and closure members for said brackets, removably secured to said brackets, said brackets being slotted, headed bolts adapted to penetrate said slots with the heads in the space between said brackets and said extended member, said closure members being apertured to permit the penetration therethrough of the shanks of the bolts and means associated with the bolts for locking the assembly so formed together.

45 6. In a shaft bearing, a relatively extended supporting member, bearings for the shaft including brackets secured to the extended member and adapted to receive the shaft, and closure members for said brackets, removably secured to said brackets, said brackets being slotted, headed bolts adapted to penetrate said slots with the heads in the space between said brackets and said extended member, said closure members being apertured to permit the penetration therethrough of the shanks of the bolts and means associated with the bolts for locking the assembly so formed together, the distance between the apertures of the closure members being insufficient to permit the bolts to escape laterally along the slots in the brackets when the bolts penetrate the closure member.

60 7. In a support for shafts, a relatively extended supporting member, bearings for the shaft including brackets secured to the ex-

tended member and adapted to receive the shaft, and closure members for said brackets, removably secured to the brackets, a base plate for the shaft including bearing sleeves through which the shaft passes, and brackets upon which said base plate is removably mounted.

8. In a support for shafts, a relatively extended supporting member, bearings for the shaft including brackets secured to the extended member and adapted to receive the shaft, and closure members for said brackets, removably secured to the brackets, a base plate for the shaft including bearing sleeves through which the shaft passes, and brackets upon which said base plate is removably mounted, the brackets for shaft and base plate being slotted, headed bolts adapted to penetrate said slots with the heads in the space between said brackets and the opposite face of the extended member, said closure members and base plate being apertured to permit the penetration therethrough of the shanks of said bolts, and means associated with the bolts for locking the assembly so formed together.

Signed at Chicago, county of Cook, and State of Illinois, this 17th day of Sept., 1931.
